UNITED STATES PATENT OFFICE

2,594,108

AIR DRIER

Dwight Elivit Woodbridge, Brooklyn, N. Y.

Application February 8, 1950, Serial No. 143,071

2 Claims. (Cl. 183—4.5)

1

This invention relates to air drying means which may be used advantageously as a part of an apparatus for drying hair of persons as is done in beauty parlors and like establishments.

The principal object of the present invention is the provision of air drying means of the indicated character which embodies improvements in construction and operation as will hereinafter appear from the following specification, when read in conjunction with the accompanying drawing in which.

Fig. 1 is a vertical sectional view of an air dryer embodying the features of the present invention, certain portions being shown in elevation and others being broken away.

Fig. 2 is a sectional view taken on the line 2—2 of Fig. 1.

Referring now more particularly to the drawing, it will be apparent that the dryer includes a cylindrical casing 10 having a side wall 11, a bottom wall 12 and a transverse partition or header wall 13 arranged above and in spaced relation to the wall 12 providing a distributing chamber 14. An atmospheric air inlet 15 formed on or connected with the wall 11 communicates with the chamber 14. The casing 10 has a top header wall 16. The wall 16 together with the cylindrical side wall 11 and the partition 13 form a chamber 17 extending from the partition 13 to the top wall 16. An outlet 18 is formed on or connected with the wall 11 in communication with the chamber 17.

Cooling means consisting of air tubes 19 are arranged in spaced parallel relation to each other. They have their opposite lower and upper ends secured to the partition 13 and the top wall 16 respectively. A hood 20 is arranged over the top wall 16 and is secured to the casing 10. A perforated disk 21 is arranged within the hood 20 for sliding movement into different positions of adjustment with respect to the tubes 19. The disk 21 serves as a damper or regulator to control the flow of air through the tubes 19 and out of the hood 20 for a purpose to appear.

A desiccant 22, such as activated alumina, or other suitable dehydrating agent fills the chamber 17 from the partition 13 to a point just below the outlet 18. The desiccant adsorbs moisture from the atmospheric air caused to flow through it from the chamber 14 by virtue of a multiplicity of apertures or ports 23 in the partition 13. The air is caused to flow by a motor driven blower 24 which operates in the inlet 15. The air is also heated because of an exothermic action resulting from the adsorption. The dehydrated or dried air flows out through the outlet 18 to be used for any purpose, such as drying hair. It is to be understood that a suitable air distributor or applicator will be connected with the outlet 18 for the intended purposes.

2

Atmospheric air after entering the chamber 14 is divided by the partition 13 so that some flows through the ports 23 as explained above, and some of the air passes upwardly through the tubes 19. The air passing through the tubes 19 cools the desiccant and incidentally reduces the temperature of the dehydrated air by dissipating the heat generated by the exothermic action resulting from the adsorption.

By adjusting the disk 21, the cooling effect of the air flowing through the tubes 19 with a corresponding change in the temperature of the air may be modified at will.

A motor driven blower 25 operating in the outlet 13 may be used to augment the action of the damper or regulator 21 by accelerating or decelerating the outflow of the dehydrated air.

After the desiccant 22 has become waterlogged, it is reactivated by steaming out the water content. For this purpose use is made of tubes 26 in each of which is disposed an electrical heating element 27. The tubes 26 have their lower and upper ends secured to the partition 13 and top wall 16, respectively, and are embedded in the desiccant. It is to be understood that the dryer will not be in normal operation during the reactivation of the desiccant. The electrical connections and source of energy for the heating elements 27 have been omitted for the sake of clearness.

I claim:

1. An air dryer including a hollow body having a main chamber, an air inlet chamber at one end of the main chamber, said main chamber having header walls and an outlet, a desiccant within said main chamber, one of said header walls having apertures therein whereby atmospheric air may be caused to flow from the inlet chamber to said outlet through the desiccant to be dehydrated, and tubes connected with the header walls extending through the desiccant and communicating with the inlet chamber, for the passage of air from the inlet chamber through said tubes, for the purpose of cooling the dehydrated air.

2. An air dryer as set forth in claim 1, and means for regulating the flow of air through the tubes to modify the cooling effect thereof.

DWIGHT ELIVIT WOODBRIDGE.
